CLAIM

The ornamental design for a string light, as shown and described.

DESCRIPTION

FIG. 1 is a front, right side, top perspective view of a string light showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged detailed view of the electrical power control box shown in the region 8 of FIG. 1; and,

FIG. 9 is an enlarged detailed view of the last one of the light bulbs forming the string light, as shown in the region 9 of FIG. 1.

The broken lines depict portions of the string light that form no part of claimed design.

1 Claim, 9 Drawing Sheets
